UNITED STATES PATENT OFFICE.

HARRY L. STEEB, OF ROCK ISLAND, ILLINOIS.

DESIGN FOR A BOOK END.

Application filed June 30, 1927. Serial No. 22,622. Term of patent 3½ years.

To all whom it may concern:

Be it known that I, HARRY L. STEEB, a citizen of the United States, residing at Rock Island, in the county of Rock Island and State of Illinois, have invented a new, original, and ornamental Design for Book Ends, of which the following is a specification, reference being made to the drawing, forming a part thereof.

In the drawing Fig. 1 is an elevation of a book end showing my new design and Fig. 2 is a perspective view thereof.

I claim:

The ornamental design for a book end as shown.

HARRY L. STEEB.
